UNITED STATES PATENT OFFICE.

HIRAM B. BROWER, OF QUAKER FARMS, CONNECTICUT, ASSIGNOR TO
FRANK W. WOOD, OF NEW YORK, N. Y.

DUST-GUARD.

SPECIFICATION forming part of Letters Patent No. 679,880, dated August 6, 1901.

Application filed November 28, 1900. Serial No. 38,006. (No model.)

To all whom it may concern:

Be it known that I, HIRAM B. BROWER, a citizen of the United States of America, and a resident of Quaker Farms, New Haven county, 5 and State of Connecticut, have invented certain new and useful Improvements in Dust-Guards for Car-Axes, of which the following is a specification.

My invention consists of an improved construction of dust-guards for car-axes in adjustable parts for taking up the wear, and particularly for being readily detachable for renewing worn-out or damaged parts, as hereinafter described, reference being made to 15 the accompanying drawings, in which—

Figure 1 is a longitudinal vertical section of a car-axe box and a dust-guard thereon of my improved construction. Fig. 2 is a transverse section of the axe and axle-box on line 20 2 2 of Fig. 1. Fig. 3 is a side elevation of my improved dust-guard, on an enlarged scale and with some parts broken out. Fig. 4 is a transverse section on line 4 4 of Fig. 3.

In the first place I provide a sheet-metal case for holding the several parts together, said case comprising the plate *a*, having side flanges *b* *b'* perpendicular to it, said case being of suitable dimensions to fit in the usual packing-recess *c* of the axle-box *d* and being 25 centrally perforated for the axe *e* to pass through it, and the flanges *b'* have inwardly-turned short flanges *b*² for keepers to packing-pieces *f*, of wood or other suitable material, extending from top to bottom of the case 30 inside of flanges *b* and being notched along the middle of their inner edges, as at *g*, to close on parts of the circumference of the axe—say about one-fourth part each. These packing-pieces are placed in position by 35 entering them between flanges *b*², so as to lodge against the inside of plate *a*, and sliding them outward each way respectively between said flanges *b*² and the plate. Compression-springs *h* are lodged in sockets *i* in the outer edges 40 of these packing-pieces *f* and bearing against flanges *b* to maintain bearing contact with the axe. In this case coiled springs are represented; but flat or other springs may be used, as desired. Between these packing-

pieces *f* other short pieces *j* are inserted, being tongue-and-grooved together with them. They are shaped on the inner ends *k* to fit the rest of the circumference of the axe. Being shorter than the diameter of the hole for the axe formed by the notches *g* *k* of the 55 several parts, these pieces *j* are applied by inserting them at the center space and sliding them outward. They also have springs *h* to maintain contact with the axe. The notches *g* are not at the beginning so deep as to permit the tongue-and-groove joints to close, as indicated by the dotted lines *l* and solid lines *n*, and thus allow the side pieces considerable wear before being obstructed by the joints. When worn to such extent that the joints 60 close up, the side pieces can be readily taken out and renewed. The other pieces *j* will wear indefinitely. Any equivalent lap-joint may be substituted for the tongue-and-groove joints. 70

The side pieces *f* are rabbeted at the ends, as shown at *m*, where the flanges *b*² overlap them to the depth of the thickness of said flanges, so that the packing-pieces may fill the case flush with the edges of flanges *b*, and 75 thus entirely fill the packing-recess *c* in the axle-box.

It will be seen that the case is of a character that may be constructed cheaply by stamping or pressing it in sheet metal, and thin and 80 light material may be used.

What I claim as my invention is—

1. In a dust-guard for car-axes, the combination of a case comprising a plate centrally perforated and provided with perpendicular side flanges, with keeper-flanges on two of the side flanges, side packing-pieces confined within said case by said keeper-flanges, and intermediate packing-pieces confined by said side packing-pieces, said packing-pieces all 85 adapted to converge on the axe, and means for causing such convergence.

2. In a dust-guard for car-axes, the combination of a case comprising a plate centrally perforated for the axe and provided with perpendicular side flanges, and keeper-flanges; side packing-pieces notched at the middle of one edge to bear against the axe and being 90

confined at the ends by said keeper-flanges, short packing-pieces intermediate of the side packing-pieces and notched at one end to bear against the axle, and being confined by 5 lap-joints with the side pieces, said several packing-pieces adapted for converging movement against the axle, and springs intermediate of said packing-pieces and the case-flanges to cause said converging movement,

and said dust-guard adapted for application to the packing-recess of the axle-box.

Signed at Seymour, Connecticut, this 26th day of October, 1900.

HIRAM B. BROWER.
